METHOD OF FORMING VALVE BAGS

John N. Tooker, Canajoharie, N. Y., assignor to
Bartlett Arkell, New York, N. Y.

Application August 29, 1934, Serial No. 741,892

4 Claims. (Cl. 93—35)

The present invention relates to a method for use in the manufacture of valve bags and especially multi-ply paper bags having pasted or satchel ends.

One of the objects of the invention is to provide a method, capable of being carried out cheaply and expeditiously, of manufacturing valve bags of the character indicated in which the valves are so formed as to ensure tight closing thereof when the bags are filled.

Other objects of the invention and advantages of the new method will be apparent as the description proceeds.

For an understanding of the invention, reference should be had to the accompanying drawings, in which

Figure 1 is a plan view of a bag tube illustrating the first step in the method of forming the bag;

Figs. 2 and 3 are views illustrating successive steps in the forming of the valve end of the bag;

Fig. 4 is a plan view of the valve end of the completed bag;

Figs. 5 and 6 are perspective views of the valve end of the completed bag showing the valve in open and closed position, respectively;

Fig. 7 is a vertical sectional view along the line 7—7 of Fig. 6;

Fig. 8 is a side view, partly in section and partly diagrammatic, illustrating the novel features of the bottoming machine;

Fig. 9 is a transverse sectional view taken along the line 9—9 of Fig. 8 and

Fig. 10 is an enlarged detail view showing portions of the convex fold forming members of the machine of Figs. 8 and 9.

The bag produced by my improved method is of the type of the one described and claimed in the pending application of Alfred Du Bois, Ser. No. 710,403, filed February 9, 1934.

In forming a pasted or satchel ended bag, a paper tube of the desired number of plies is first cut by any suitable means into bag lengths such as indicated at 2 in Fig. 1. Each bag length has the usual serrated edges 4 and a centrally disposed tab 6 on one wall thereof at one end with a corresponding cut out 8 of the same wall at the other end. To form a pasted end bag, each such bag length is first cut longitudinally at one end to form slots 10. The slotted end of the bag length is then spread and flattened into the position indicated in Fig. 2, with the end flaps 12 and 14 between corresponding slots 10 folded inwardly toward the axis of the bag and wall portions 16 and 18 spread. Paste, indicated at 20

(Fig. 3), is then applied over the surface of wall portion 16 and over the greater part of the inwardly folded flap 12. No paste is applied to the flap 14, which serves as the valve when the bag is completed.

In the bag of said Du Bois application, the under flap of the valve is scored or creased to form a hinged portion which is so arranged that it tends to snap firmly and tightly into engagement with the upper wall of the valve throughout the overlying portion thereof when the bag is filled and the filling tube is withdrawn.

In accordance with the present invention, such scoring or creasing is performed at the stage of the bag manufacture when its end is in spread and flattened condition as above described, the creasing being done on lines 22 and 24.

As in the bag of said Du Bois application, these creases 22 and 24 together form a V having its apex on the infolded median fold 26 of the bag tube and with legs extending away from the adjacent end of the bag tube to the folds 28 and 30 forming the edges of flap 14. This V-shape crease, which is convex on the outer surface of flap 14, divides the flap area into a substantially diamond shape portion indicated at 32 and a portion, indicated at 34, lying between the end of the tube and the folds 28 and 30. After the creases 22 and 24 are formed, the end of the bag tube is scored along parallel lines 36 and 38.

Score 36 extends transversely of the bag from the junction of folds 22 and 28 and similarly score 38 extends transversely of the bag from the junction of folds 24 and 30. Wall portion 18 is then folded inwardly upon score line 38 and wall portion 16 is similarly folded inwardly upon score line 36 to form overlapping side flaps, and the folded parts pressed firmly together to cause the paste to seal all of the end of the bag except the valve flap 14.

In the so completed bag end, the convex fold or crease 22 of the valve lies adjacent the portion of the fold 28 lying between the end of score 36 and slot 10, and crease 24 lies adjacent the portion of the fold 30 lying between the end of score 38 and the corresponding slot 10. During filling, the end of the filling tube, indicated in dotted lines in Fig. 5, depresses the valve flap and forces the creases 22 and 24 downwardly. When the bag is filled and the filling tube removed, the convex creases 22 and 24 cause the valve flap to snap into the position indicated in Figs. 6 and 7 in which a tight closure of the bag is effected and the creases are positioned adjacent the upper folded edges of the flap to form a seal therefor.

Upon closure of the valve, as shown best in Fig. 7 the central portion of area 36 of flap 16 lies flush with the top surface of the bag formed by the pasted overlapping wall sections 16 and 18, reinforcing the end of the bag and preventing seepage of the contained material toward the valve.

A machine adapted to carry out automatically the above described method is illustrated in Figs. 8, 9 and 10. The machine is of the general type now in use and known as a bottoming machine, but is modified to include means for forming the convex folds or creases hereinbefore described in connection with Figs. 1 to 7 inclusive.

The machine includes the usual roll 40 and associated means (not shown) for forming the slots 10 and for spreading the end of the tube, the usual flattening drum 42, a pasting segment 44 cooperating with a drum 46 and receiving paste from a paste roller 48 through the intermediary or roller 50, and scoring rollers 52 for forming the transverse scores or creases 36 and 38. Pasting segment 44 is rigidly secured to a shaft 54 for rotation thereby, and drum 46 is similarly secured to and rotated by a shaft 56, shafts 54 and 56 being suitably driven in timed relation by means of gears 58. In order to adapt the machine to carry out my improved method, an arm 60 is rigidly secured at one end to shaft 54 to be rotated thereby. The other end of arm 54 carries a block 62 having a V-shaped groove 64 therein which is disposed with its apex toward the pasting segment and its arms extending substantially at right angles thereto. An arm 66 having at one end thereof a V-shaped projection 68 for cooperation with the groove 64, is secured to drum 46 by means of a pin 70 to rotate therewith.

Adjacent the creaser arms 60 and 66 and rigidly mounted on shafts 54 and 56 is one pair of aligned pulleys 72 for engaging one lateral edge of the bag tube during passage thereof between the creasers and between the drum 46 and the pasting segment. A similar pair of aligned pulleys 74 is provided for engagement with the other lateral edge of the bag. Thus, as the flattened end of a bag tube advances from beneath the pressure roller 42 and passes over the drum 40 with its edges guided and held by pulleys 72 and 74 a portion 76 of the pasting segment 44 first applies paste to wall portion 16. Immediately thereafter, during the application of paste to flap 12 by a portion 78 of the pasting segment, the arms 60 and 66 move into position where projection 68 enters groove 64 and forms the convex creases 22 and 24. In Fig. 10 the creasers are shown just prior to engagement. When the end of the bag length advances into position between rolls 52 the transverse scores 36 and 38 are formed.

Thereafter the wall portions 16 and 18 are folded by any suitable means (not shown) along the score lines 36 and 38 and pressure is applied to the pasted portions. The bag length may then be run through another bottoming machine so as to close its other end in the usual manner.

It will be apparent as the desired creasing to

form the hinged portion in the under flap of the valve is preferably effected during the operation of closing the valve end of the bag tube, that this may be accomplished without interrupting such operation. The creasing or hinge forming devices may be easily applied to the usual bottoming machine and when in use do not interfere with the speed of operation of the machine.

As will be evident to those skilled in the art, my invention permits various modifications without departing from the spirit thereof or the scope of the appended claims.

What I claim is:

1. In the method of satchel ending a bag tube which includes opening and flattening the end of the tube so as to provide inwardly directed corner flaps and longitudinally extending side flaps, and folding over the side flaps in overlapping relation and pasting them together so as to provide a satchel end with one of said corner flaps constituting the under flap of a valve, the improvement which consists in the additional step of creasing the under flap of the valve when the end of the bag tube is in said opened and flattened condition so as to provide a hinged portion adjacent the end of the upper wall of the valve when the satchel end has been completed, the hinged portion tending to cause the under flap of the valve to lie tightly against the underside of the upper wall of the valve when the bag is filled and the valve is permitted to close.

2. In the making of a valve bag, the method of forming the valve which includes spreading and flattening the end of a bag tube by infolding flaps at the median edge of the tube and then forming in one flap a pair of convex creases which extend from a point on the median fold of the tube in a direction away from the adjacent end of the tube and to the folds forming the edges of that flap.

3. The method of forming valve type bags from bag tube lengths which includes infolding the valve flap and thereafter creasing the valve flap so as to provide adjacent the end of the upper wall of the valve a hinged portion which will lie tightly against the under side of the upper wall of the valve when the bag is completed and filled and the valve is permitted to close.

4. The method of forming the valve end of a bag from a bag tube which includes forming longitudinal slits at one end of the bag tube, then spreading and flattening the slitted end of the tube to form infolded flaps between corresponding slits, thereafter applying paste to one of the flaps and to the end of one wall portion between said flaps, forming a V-shaped crease, convex to the outer surface of the bag, on the unpasted flap positioned with its apex on the median edge of the tube and its legs extending outwardly away from the adjacent end of the tube, and finally folding over the walls of the tube end along transverse lines terminating at the ends of the legs of said V-shaped crease.
